UNITED STATES PATENT OFFICE

JACOB R. SENSIBAR, OF CHICAGO, ILLINOIS

CENTRIFUGAL PUMP

Application filed June 23, 1926. Serial No. 117,984.

This invention relates to centrifugal pumps and the like and is particularly adapted for use in pumping mixtures of sand, gravel, and water.

5 The primary object of this invention is to provide a centrifugal pump which will withstand the excessive wear incident to pumps of this type where the sand, gravel, and the like carried by the water is of an abrasive nature, and at the same time to provide a ready means of renewing those parts of the pump where excessive wear is bound to occur.

Another object is to provide means for preventing sand from getting into certain parts of the pump which move relatively to each other and where the presence of such sand would necessarily cause a great deal of wear.

Another object is to provide a pump of this character which is so constructed that it can be readily turned to any desired angle.

Another object is to provide a pump which, while having these several advantages, is at the same time comparatively inexpensive to manufacture and relatively easy to assemble and disassemble.

These and other objects are accomplished by this invention which is fully described in the following specification and shown in the accompanying drawings in which Figure 1 is a front elevation of the pump as viewed from the intake side showing part of the supporting saddle removed for the sake of clearness;

Fig. 2 is a vertical section on the line 2—2 of Fig. 1.

The embodiment illustrated comprises a centrifugal pump having an outer spiral casing made up of sections 10 and 11 secured together by means of bolts 12 and side or inner casing members, the one at the left or intake side being made up of two cast iron members 13 and 14, secured together by means of bolts 15, while the right hand member as shown in Fig. 2 is likewise made of two sections 16 and 17, similarly bolted together.

The lower casing portion 14 is provided with a flange 18 which is concentric with the axis of the pump and is adapted to rest upon the concentric saddle 19 which serves to sup-

port the pump casing. Likewise the lower casing portion 17 has a similar flange 20 which rests upon the concentric saddle 21.

The pump shaft 22 is journaled in a suitable bearing 23 and in a combined bearing 24 and carries upon its inner end an impeller 25, which is secured to the flange 22^a by means of cap screws 26. A central sleeve 27 is bolted to the casing sections 16 and 17 by means of cap screws 28 and carries a packing gland 29 which surrounds the shaft 22. The impeller has a heavy central hub which is internally tapered to receive the tapered end 22^b of the shaft and is further secured thereon by means of the key 22^c. The impeller has side flanges 25^a which extend substantially at right angles to the axis of the impeller shaft, so that the material passing therethrough will be guided outwardly toward the back of the spiral casing sections 10 and 11.

An intake pipe 30 is bolted to the inner casing sections 13 and 14, its axis being substantially coincident with the axis of the impeller shaft 22, the center of the impeller being cut 75 away as shown to receive the ring 31 which is bolted to the inner surface of the casing sections 13 and 14 and has an inwardly extending circular flange which lies just inside the wearing ring 32 which is secured to the front 80 face of the impeller. This ring is substantially in contact on its inner face with the flange member 31 and on its outer face with the plate ring 33 which is bored out to receive it, the plate ring being riveted to the annular plate 34, the inner face of the plate 34 being substantially flush with the inner edges of the spiral casing members 10 and 11 into which it is recessed. The plate 34 and plate ring 33 are held in place by means of 85 cap screws 35.

A similar annular plate 36 is located on the opposite side and this carries a plate ring 37 which is likewise secured in place by cap screws 38. Annular spaces 39 and 40 are 95 thus provided between the inner casing members 13, 14 and the plate 34 on the one hand and the members 16, 17 and plate 36 on the other. Clear water is supplied to these recesses through the pipes 41 from any suitable 100

source of water supply (not shown). This water, admitted as it is substantially at the point of intake to the impeller, is drawn into the pump also by the action of the pump itself and serves to keep the bearing surface of the wearing ring 32 free from said and the like, thereby preventing excessive wear of this ring.

On the side of the shaft, this water passing the plate ring 37 prevents much of the sand from getting to the wearing strip 42 which is carried by the hub of the impeller and which has a bearing on the sleeve 27^a, the space 43 between the wearing strip 42 and the packing gland 29 being preferably filled with a heavy oil or grease. The shaft 22 is driven through the coupling 44 by an electric motor or other suitable source of power (not shown).

20 The thrust bearing 24 is provided with a continuous stream of oil through pipes 66, 69, 70 and 71, the circulation of oil being effected by the pump 67, driven by a belt 68 from shaft 22 as shown in Fig. 2.

25 Thus it will be seen that a very simple form of centrifugal pump is provided and one which can readily be assembled and disassembled for the replacement of parts, or for repair. The arrangement shown, however, 30 prevents sand and grit from getting into those parts where excessive wear might occur. When wear does occur, as in the spiral casing members 10 and 11, these can readily be removed and steel welded thereon, and in 35 such a way as to return the castings to substantially their original form.

What I claim is:

A centrifugal pump comprising an outer spiral casing, inner or side casing members secured to said outer casing on the intake and shaft sides thereof, respectively, the inner casing member on the shaft side including a central sleeve in which the pump shaft is journalled, an impeller secured to the inner 40 end of said pump shaft, the side flanges of said impeller being at substantially right angles to the axis of the pump shaft, a wearing strip mounted on the impeller hub and having a bearing in said central sleeve, a 45 wearing ring secured to the front face of said impeller, the inner face of said ring being contacted with a flange member carried by an inner casing member, an annular plate recessed in said spiral casing on the intake side 50 thereof and having a plate ring secured thereto, the inner face of said plate ring being in contact with the outer face of said wearing ring, and a second annular plate and 55 plate ring recessed in the shaft side of said spiral casing, said first and second mentioned annular plates forming, together with said plate rings and inner casing members, a pair 60 of annular water spaces disposed on opposite 65 sides of the impeller and from which water is

drawn inwardly to keep the bearing surfaces of the impeller hub and wearing ring free from dirt.
